UNITED STATES PATENT OFFICE.

EDWIN C. BUCK, OF PHILADELPHIA, PENNSYLVANIA.

CABLE-RAILWAY GRIPPING APPARATUS.

SPECIFICATION forming part of Letters Patent No. 391,878, dated October 30, 1888.

Application filed May 10, 1887. Serial No. 237,697. (No model.)

To all whom it may concern:

Be it known that I, EDWIN C. BUCK, of the city and county of Philadelphia, State of Pennsylvania, have invented a new and useful Improvement in Cable-Railway Gripping Apparatus, of which the following is a true and exact description, due reference being had to the drawings which accompany and form part of this specification, and in which similar letters 5 denote similar parts.

My invention has for its principal object a gripping attachment for cable roads which in their route cross other cable roads. My improved apparatus is such as to allow one road 15 to cross the other at grade without releasing the gripping apparatus from the cable upon the other line at the point of passage.

My invention also consists in novel means to close and release the gripping jaws.

20 In the drawings, Figure 1 represents a side view of my improved grip. Fig. 2 is a section on the line 1 2 of Fig. 1. Fig. 3 is a section on the line 3 4 of Fig. 1. Fig. 4 is a view of the cover for cross-cable, showing cover closed, 25 which occurs when being crossed by the grip of cable A. Fig. 5 is a view of the cover for cross-cable, showing cover open.

A represents the cable which is being gripped; B, the cross-cable.

30 C is the floor of the car, to which by any well-known means the grip D is suspended.

a and a' are the gripping jaws. These jaws are hinged at a², and are operated by means of the rod d, which rod can be raised vertically 35 by the cam d², rod d³, and lever d⁴, said lever d⁴ having the pawl d⁵, said pawl working in the rack d⁶. The rod d is forced against the projection d' on the lower and movable jaw, a, and the jaw is held in more or less contact and 40 grips the cable according to the pressure, the rod d being connected to the frame d⁶, in which the cam d² works.

E and E' are two plates, one on each end of the grip. These plates E and E' are constructed 45 in two parts, respectively, E³ and E⁵ and E⁴ and E⁶. The parts E³ and E⁴ have on their lower ends the jaws e and e', Fig. 3, which jaws are spread or forced apart by the spring e⁷. The parts E⁵ and E⁶ surround the parts E³ 50 and E⁴, and are made wedge-shaped at their lower ends, and are capable of an independent vertical motion upon the parts E³ and E⁴, the

extent of which motion is governed by the extent of the travel of the pins e¹⁷ and e¹⁹ in the slots e¹⁶ and e¹⁸ and the parts E⁵ and E⁶, and are 55 guided in their vertical movement upon the fixed hollow guide-plate E⁷.

The gripping-jaws are suspended in the following manner: The jaw a' has an I-shaped projection or head, e², on each end, and these 60 projections or heads are suspended from the parts E³ and E⁴ of the plates E and E' by means of the jaws e and e' clasping the I-shaped projection or head e², and the jaws e and e' are held against the I-shaped projection or head e² by 65 the wedge-shaped parts of E⁵ and E⁶ of the plates E and E', respectively, which compress the spring e⁸. The parts E³ and E⁴ are suspended by means of the pin e¹⁹, resting against the end 70 of the slot e²⁰, which slot e²⁰ is in the fixed hollow plate E⁷, the pins e¹⁷ and e¹⁹ being fixed to the plates E³ and E⁴. Upon the upper and 75 fixed jaw, a', are the tapering wings F and F', and attached to each of the parts E⁵ and E⁶ on the plates E and E' are the tapering wings G and G', tapering oppositely to the corresponding wings on the fixed jaw.

When the car is moved in the ordinary manner, the jaws and the plates assume the position shown on the right-hand portion of Fig. 1. 80 The cable being gripped, the car approaches a cable road running at an angle with it. The cross-cable, which is represented in the drawings by the letter B, strikes the wing F, which causes said cable B to travel up and strike the wing G, attached to the portion E⁵ of the plate E, which forces said part E⁵ upward, releasing the jaws e and e', and allowing the spring e⁷ to spread, freeing the jaws e and e' from the head e² of the gripping-jaw a', and the gripping-jaws therefore fall below the cross-cable and allow it to pass. When the movement of the cross-cable has caused E⁵ to move up to the extent of travel of the pins e¹⁷ and e¹⁹ in the slots e¹⁶ and e¹⁸, the parts E⁵ and E⁶ of the plate 85 E move vertically together, working against the spring H, which is in the interior of the fixed plate E⁷ and compressing said spring H. The movement of the plate E⁵ is guided by the interior of the fixed plate E⁷, which plate is 90 hollow, as heretofore described. On the rear end of the portion E⁵ of the plate E is the projecting tongue g', by means of which the cross-cable retains the parts E³ and E⁴ of the plate 95

E in an elevated position until the cross-cable has entirely passed that portion of the grip. When the cross-cable has entirely passed the plate E—that is, passed beyond the projecting tongue g—the pressure on the spring H is released, and the spring H causes the portions E³ and E⁵ to return downward together until the pin e¹⁹ reaches the end of the slot e²⁰, when the portion E⁵ has its independent movement upon the portion E³ and again causes the jaws e and e' of the part E³ to clasp the I-shaped projection or head e² on the jaw a', and the portion E⁵ is suspended by the ends of the slots e¹⁶ and e¹⁸, resting, respectively, against the pins e¹⁷ and e¹⁹ of the plate E³.

The rod d is made independent of the projection d', and when another cable road is to be crossed this rod d is elevated, so that the cross-cable can pass between the rod d and the projection d', and the grip is retained closed to the main cable by means of the bed I, placed in the conduits at the crossing-points, and thus the cable is not released in crossing another cable road. The operation upon the other plate, E', is similar to that heretofore described, and the cross-cable thus passes both plates E and E' and the entire gripping apparatus.

In order to avoid the wear upon the cross-cable at the point of crossing I can inclose the cable at the crossing-point with a pipe-shaped cover, (shown in Figs. 4 and 5,) the upper half, K, of which is hinged. This pipe-cover is normally held open by the spring O. When the cable is to be crossed, the wings of the grip strike the cover of the cross-cable, closing it, and thereby avoiding the friction upon the cable, and when the cross-cable is the one operating, the grip, as is well known, lifts the cable above the position it occupies when it is on the pulleys in the conduit when not in use. Therefore when a car, with its grip connected to said cable, approaches a crossing where the cable is provided with a pipe-cover the cable, being lifted by the grip, as heretofore described, is elevated above the hinged portion of the pipe, and therefore the grip passes said cover without striking it.

I do not limit myself to mechanism for operating the grip-jaws, nor to any particular construction of said grip-jaws.

Having now fully described my invention, what I claim, and desire to protect by Letters Patent, is—

1. In a gripping apparatus for cable railways, in combination, gripping-jaws, means to operate said jaws, wings upon the fixed jaw of said jaws, plates to suspend said jaws, said plates being capable of an upward motion off of said jaws, and wings attached to said plates. 55

2. In a gripping apparatus for cable railways, in combination, gripping-jaws, means to operate said jaws, wings upon the fixed jaw of said jaws, plates to suspend said jaws, said plates being capable of an upward movement 60 off of said jaws, wings attached to said plates, and tongues g, also attached to said plates.

3. In a gripping apparatus for cable railways, the plates E and E', said plates each being constructed in two parts, whereby the 70 outer part may have an independent movement upon the inner part, and a spring, H.

4. In a gripping apparatus for cable railways, in combination, gripping-jaws, means to operate said jaws, the plates E and E', jaws e 75 and e', arranged within said plates, a projection on the upper gripping-jaw, and spring e', located between the jaws e and e', whereby the gripping-jaws may be disconnected from the jaws e e'. 80

5. In a gripping apparatus for cable railways, in combination, gripping-jaws and a bed, I, substantially as and for the purpose specified. 85

6. In a cable railway, in combination, a cable, a cover for said cable, the upper part of said cover being hinged and normally open and capable of being closed, so as to cover the cable, substantially as and for the purpose specified. 90

7. In a gripping apparatus for cable railways, in combination, the plates E and E', said plates being constructed in two parts, E³ and E⁴ and E⁵ and E⁶, respectively, the plates E³ and E⁴ having spring-jaws e and e' at the ends 95 of said plates E³ and E⁴, gripping-jaws, projections upon the fixed jaw of said gripping-jaws, pins upon said plates E³ and E⁴, slots in the parts E⁵ and E⁶, a hollow guide-plate, E⁷, a spring, H, in said guide-plate, and a slot in 100 said guide-plate, all constructed and operated substantially as described.

EDWIN C. BUCK.
